UNITED STATES PATENT OFFICE.

ENOCH WHITMORE, OF SAN FRANCISCO, CALIFORNIA.

TWO-WHEELED VEHICLE.

SPECIFICATION forming part of Letters Patent No. 272,815, dated February 20, 1883.

Application filed July 17, 1882. (No model.)

To all whom it may concern:

Be it known that I, ENOCH WHITMORE, residing in the city and county of San Francisco, and State of California, have made and invented certain new and useful Improvements in Two-Wheeled Vehicles; and I do hereby declare that the following is a full, clear, and exact description of the same, reference being had to the accompanying drawings.

10 My invention relates to certain improvements in the bed and running-gear of two-wheel vehicles, by means of which I am enabled, first, to give ready and convenient access to the vehicle without climbing over the 15 wheels or entering at the front, between the wheel and the box or shafts; secondly, to remove the disagreeable jogging or shaking motion common to such class of vehicles where the body or box is supported in horizontal position from the shafts alone.

20 The following description fully explains the nature of my invention and the manner in which I proceed to construct, apply, and use it, the drawings being referred to by letters and figures.

25 In the said drawings, Figure 1 is a perspective view of the axle and frame constituting the support and running-gear. Fig. 2 is a vertical longitudinal section through the frame 30 and body. Fig. 3 is a plan or top view with the body removed.

35 A is the axle, having the usual spindles for the wheel-hubs. B B are two short bars fixed upon the axle by clips b b, and running fore and aft and parallel with each other. These bars receive and support the ends of the body-springs D D, which are placed transversely across the space, one in front of and the other at the rear end of the axle, so that they are held 40 in position upon the ends of the bars parallel with the axle.

45 Midway between the ends of the springs, or at a point where the center of the bed or body will come when placed over the springs, I fix a table, E, upon which the under side of the platform or box is directly received and supported.

50 In the construction given in Fig. 1 of the drawings I have attached the ends of the front spring beneath the ends of the bars, while connection of the ends of the rear spring is made upon the top of the bars. The effect of

this is to bring the highest part or centers of the two springs out of horizontal line, and to render it necessary to support the front end of the table E by a short post or standard, g; but if both springs are connected to the bars B B in the same manner the table and springs can be secured together without such standard. This table affords a bearing, h, for a short upright bolt or shaft, H, carrying a pinion, I, fixed on its end beneath the table, and having its upper end let into and secured to the floor or bottom of the vehicle-body.

A segment-rack, K, pivoted at m to the under side of the table, engages with the pinion I in such manner that rotation of the shaft is effected at any time by moving the rack K about its center of motion, and the vehicle-body being therefore secured to the end of the pinion-shaft, movement of the bed to one side or the other upon this central point results from such action of the rack upon the pinion. To work this rack, a bar, n, fixed to the rear end of the table, is carried to one side beneath the body and beyond its side to give support for a lever, N. At this point the lever N is fulcrumed, and is held perpendicularly in position to bring its longer end or handle upward in convenient position alongside of the body, where it can be readily grasped by a person seated in the vehicle. Its shorter end is connected to the outer end of a rod or bar, R, that runs to the center of the table, and is fixed to the rear or pivot end of the rack. By 85 throwing this handle to one side or the other, rotary movement of the rack is produced from the driver's seat, and the vehicle-body is caused to swing or turn upon the table to one side or the other; also, by bringing the lever to the vertical, the body is caused to assume its normal or longitudinal position. The body of the vehicle is therefore cramped or turned to one side at such operation, and affords ample room for a person to enter or alight from the vehicle 90 at either side from behind the axle.

95 A suitable locking device can be provided on the side of the body to hold the lever in fixed position.

The table E has several rollers, s s, let into its top to bear the weight of the bed above and reduce friction, a ring or plate, u, being fixed to the bottom of the bed to take the wear of the rollers.

The shafts T are secured at the inner ends to a stiff frame formed of side bars, V V, which extend along from front to rear, just inside the wheels and parallel with the sides of the bed, 5 and are connected to the bars B on the axle by means of curved braces t t, that spring from the front and rear ends of the bars B, and extend upward and outward. A cross-bar, W, and a curved brace, X, connect these side bars 10 together at the front, and complete this frame for the shafts; but the rear of the frame is open.

It will be noticed in the above construction 15 that the shafts have no direct connection with the body, and that the springs run transversely across beneath it and parallel with the axles, the effect of which is to overcome the disagreeable rocking or jogging motion of the bed and render the riding easy and comfortable. 20 This construction affords a more convenient and safer access to two-wheel vehicles, as it permits entrance and exit without passing over the wheels or crowding in between the animal and the wheel at the front. Ample room is 25 afforded to enter or pass out from the body at the rear, and it can be turned into an oblique position and back again upon its supporting-table by a simple movement of the hand-lever.

To insure a steady action of the segment, as 30 well as to relieve the bolt H of lateral strain, I carry out from the end, where the connecting-rod is attached, and in a rearward direction under the bed, a strap, Y, the end of which is hooked or bent, to take over a circle-iron, Z, fixed to the back of the body. The 35 radius of this circle is equal to the length of the strap, and by the hooked end it is held down while it moves from side to side over the curve.

40 Having thus fully explained my invention, what I claim, and desire to secure by Letters Patent, is—

1. A two-wheel vehicle having its bed or body mounted on a central pivot, whereby it is adapted to be crimped to afford entrance at 45 the side between the wheel and body.

2. The combination, in a two-wheel vehicle, of a body pivoted to the frame of the running-gear, so as to be capable of turning independently thereof, and mechanism, substantially as 50 described, for turning the body to one side or the other and back again, for the purpose set forth.

3. In a two-wheel vehicle, the combination 55 of the transverse springs, the table fixed thereon, the bolt or shaft having bearings on the table, and fixed at its upper end to the receptacle bed or body, and means, substantially as herein described, for rotating said shaft to turn the vehicle body upon its table, for the purpose 60 set forth.

4. In a two-wheel vehicle, the body-supporting gear, consisting of the axle, the bars B, the transverse springs D, supported by the said bars, and the table to receive and hold the bed 65 or body.

5. In a two-wheel vehicle, the combination 70 of the body-carrying frame B B D D and the shaft-carrying frame B V t, secured to the axle, but independent in its connection with 75 and detached from the body or bed, substantially as described.

6. The combination, with the bed or body, of the table having roller-bearings, the bolt H, mounted and capable of rotating in bearings through the table, the pinion fixed on the bolt H, the segment-rack K, and the hand-lever and connection N R, applied to operate as and for the purpose set forth.

Witness my hand and seal.

ENOCH WHITMORE. [L. S.]
